UNITED STATES PATENT OFFICE.

ALBERT HENRY SIMMONS, OF ORLAND, CALIFORNIA.

WATER-LEVEL-REGULATING DEVICE.

1,259,791.

Specification of Letters Patent. Patented Mar. 19, 1918.

Application filed May 14, 1917. Serial No. 168,415.

To all whom it may concern:

Be it known that I, ALBERT HENRY SIMMONS, a citizen of the United States, and a resident of Orland, in the county of Glenn 5 and State of California, have made certain new and useful Improvements in Water-Level-Regulating Devices, of which the following is a specification.

My invention is an improvement in water 10 level regulating devices, and has for its object to provide mechanism of the character specified used in water troughs, which will be automatically operated to admit the water from the source of supply when the water 15 falls below a predetermined level and will always retain the water at a certain level in the trough.

Figure 1 is a vertical section through the improved valve and trough.

Fig. 2 is a side view of the float and valve casing.

Fig. 3 is a top plan view of the float casing and.

Fig. 4 is a perspective view of the upper 25 section of the valve casing.

The present embodiment of the invention is shown in connection with a water trough 1 of usual construction, having in the bottom thereof an opening 2, through which is 30 passed the supply pipe 3 for the water, a packing 4 encircling the pipe 3 within the opening 2. A substantial spherical valve casing is connected with the top of the pipe 3 within the trough, the said casing consisting of a lower section 5 and an upper section 6, and the sections are flanged as shown at 7 to permit them to be connected together in the manner to be presently described.

The upper end of the pipe 3 is threaded 40 into a nipple 8 at the center of the lower section and the upper section 6 is provided at its center with a port 9. A ball valve cooperates with this port being arranged with- 45 in the casing 5 and 6, and the valve is con-

nected by a stem 11 with a float 12. The float and the stem are inclosed by substantial cylindrical casing 13, which has its upper end closed, as shown, and provided with a series of openings 14 for insuring that 50 pressure within the float casing will be atmospheric. This float casing has a marginal flange 16 at its open end which rests upon the flanges 7 of the section 6 of the valve casing, and the three flanges are 55 secured together by bolts and nuts 15.

Whenever the water in the trough reaches a predetermined level, the float will close the valve 10 against the port 9, sealing the said port, and preventing the further inflow 60 of water. As soon as the water falls below the predetermined level, the float will drop and the valve will open permitting the water to enter the trough to replace that removed. Thus the water is retained at a predeter- 65 mined level.

It will be noticed that the valve is pivoted to the stem so that it may move freely with respect to the stem to permit it to seat properly, and that the cylindrical casing has discharge openings 17 for the water. 70

I claim:—

In combination with a trough and a supply pipe leading thereto, of a substantially spherical valve casing at the top of the pipe 75 and connecting with the pipe and having a port at its top, a ball valve within the casing coöperating with the port, a float, a stem connecting the float to the valve, a casing inclosing the float and secured to the valve 80 casing and having openings in its top for equalizing the air pressure within the casing and also having discharge openings in its side below the float, said spherical casing being sectional and the sections having marginal flanges abutting, the float inclosing casing having also a marginal flange abutting the flanges of the sections, and means for securing the flanges together. 85

ALBERT HENRY SIMMONS.
